UNITED STATES PATENT OFFICE.

JOHN HOWARD WAY, OF PHILADELPHIA, PENNSYLVANIA.

HINGE.

1,345,524.

Specification of Letters Patent.

Patented July 6, 1920.

Application filed May 9, 1919. Serial No. 295,966.

To all whom it may concern:

Be it known that I, JOHN HOWARD WAY, a citizen of the United States, residing in the city and county of Philadelphia and State 5 of Pennsylvania, have invented certain new and useful Improvements in Hinges, whereof the following is a specification, reference being had to the accompanying drawings.

The invention relates to hinges such as are 10 ordinarily employed in the mounting of doors, shutters, sashes, or other similar building appurtenances.

The invention is more especially directed 15 to means for preventing independent rotation of the hinge pintle, and is applicable either in ordinary leaf hinges, or in adjustable hinges in which the pintle is formed with relatively concentric and eccentric sections, such as shown and described in the 20 United States Patent No. 1,208,422, granted me, under date of December 12, 1916. In the former instance, the improvement is advantageous in preventing the pintle from working out, due to induced independent 25 rotation, and in the latter instance, to fix the pintle in adjusted positions.

The invention is further directed to a 30 socket member for sustaining the end of the pintle, said member being provided with simple means functional in rigidly retaining the same in one of the hinge knuckles, and so constructed as to facilitate ready assembling initially.

The organization characteristic of my 35 invention involving the advantages above pointed out, will be best understood from the detailed description which follows:

In the drawings, Figure I, is a face view 40 of a hinge conveniently embodying my invention, the interfitting pivot knuckles being shown in section.

Fig. II, is a cross section through the hinge, as viewed in the direction of the arrows II-II, in Fig. I.

Fig. III, is an elevation of the socket member within which the end of the pivot 45 pintle is sustained, and

Fig. IV, is a modified form of my invention.

In its general aspect, the hinge which I 50 have herein illustrated is similar to the structure set forth in the patent above referred to. In this instance, the hinge leaves are represented at 1, and 4, the former being provided with the pivot knuckles 2, 3, and the latter with the interfitting knuckles

5, 6, 7. The coöperative pivot pintle comprises the concentric sections 8 and 9, and an intermediate eccentric section 10. The sections 8 and 9, are respectively sustained 60 in the knuckles 5 and 7, of the leaf 4, while the knuckles 2 and 3, of the plate swing about the eccentric section 10, of the pintle.

In order to facilitate the rotative adjustment of the pintle, it is supplemented at its 65 upper end with a head 11, slotted at 12, so as to be engageable by a screw driver, or other suitable implement available for the purpose. By this construction, it will be readily seen that the pivotal axis of the 70 hinge may be adjusted so as to compensate for any inaccuracies in initial mounting of a door or any binding that may subsequently occur through warping or shrinkage.

For the purpose of preventing rotation of 75 the pintle after the desired adjustment has been obtained, the same has been provided with an enlargement 13, having the polygonal cross sectional configuration clearly shown in Fig. II. This enlargement 13, is 80 preferably formed integrally with the pintle, directly beneath its head 11, and adapted to engage within a correspondingly shaped socket formed in the outer knuckle 5, of the leaf 4.

While the enlargement 13, and its socket 85 may have any appropriate configuration, the octagonal form shown serves the purpose satisfactorily in practice. It will be noted from Fig. I, that the sides of the polygon 90 are somewhat concaved so as to afford, by reason of the sharper corners thus formed, a firmer interlock than would be possible by a straight sided configuration.

The anti turning feature above described, 95 while it is more particularly necessary in an adjustable hinge, such as herein illustrated, may however be incorporated to advantage in an ordinary hinge to prevent the pintle from shifting longitudinally in the 100 hinge knuckles, as often happens through induced independent rotation.

As will be observed from Fig. I, the lower reduced end 9, of the pintle is sustained within an opening 15, formed in a socket member 16. Said member has a substantially cylindrical inner extremity 17, (Fig. III) which is received in the hinge knuckle 7, and formed with a peripheral projection 18, which co-acts with a correspondingly 110 shaped internal groove within the knuckle, in preventing displacement. It will be

- noted that the projection 18, is tapered, so that in assembling, the knuckle is slightly expanded until the projection finds its seat within its coöperative groove. By this arrangement, the socket member 16, is rigidly held in place in opposition to any force applied to the pintle, for example, by hammering, this method of assembling hinges being invariably resorted to in practice.
- 10 The feature just described may also be employed to advantage in ordinary hinges for analogous considerations, especially where the pintles are slightly longer than actually necessary, and the force of the hammer blow, as a consequence, directly transmitted to the socket member. Said member is preferably provided with a spherical head 19, which serves as an ornamental counterpart of the pintle head 11.
- 20 Fig. IV, shows a modified form of my invention as applied to a "butt" hinge wherein the knuckle 20, is integrally cast or forged with the leaf 21. In this instance, the equivalent of the "socket", hereinbefore described, is in the form of a recess 22, having parallel sides prolonged in one direction to the edge of the knuckle. These parallel sides coöperate with opposite faces of the polygonal portion of the hinge pintle, the latter being represented in dotted lines at 30 23, in the figure. The socket parallel sides prolonged to the edge of the knuckle as thus described, is entirely effective, and much more easily formed especially in a cast leaf.
- Having thus described my invention, I 35 claim:
- In a hinge, the combination of a pair of leaves formed with interfitting pivot knuckles; a coöperative pintle provided at one end with a head; a socketed member for 40 sustaining the opposite end of the pintle, said member being provided with a peripheral shoulder serviceable as a retainer in coöperation with an internal groove in one of the hinge knuckles, and formed with a 45 tapering approach functional, during assembling, in expanding the knuckle until the shoulder finds its seat within the groove.
- In witness whereof, I have hereunto signed my name at Philadelphia, Pennsylvania, this 2nd day of May, 1919.
- JOHN HOWARD WAY.
- Witnesses:
- JAMES H. BELL,
E. L. FULLERTON.
